UNITED STATES PATENT OFFICE.

MARCENE BENN, OF WESTFIELD, PENNSYLVANIA.

SHOE-CLEANING DEVICE.

965,363.

Specification of Letters Patent. Patented July 26, 1910.

Application filed March 8, 1910. Serial No. 548,016.

To all whom it may concern:

Be it known that I, MARCENE BENN, a citizen of the United States, residing at Westfield, in the county of Tioga and State 5 of Pennsylvania, have invented certain new and useful Improvements in Shoe-Cleaning Devices, of which the following is a specification.

My invention relates to improvements in 10 shoe cleaning devices, the object of the invention being to provide an improved device of this character adapted to be located outside of the house, adjacent the entrance, and which will permit a caller to thoroughly 15 clean his or her shoes before entering the house.

A further object is to provide an improved device of this character which will not only permit the shoes to be scraped to 20 free them from mud sticking to the soles, but which will permit the shoes to be brushed to thoroughly cleanse them.

With these and other objects in view, the invention consists in certain novel features 25 of construction, and combinations and arrangements of parts as will be more fully hereinafter described and pointed out in the claims.

In the accompanying drawings: Figure 1, 30 is a view in side elevation illustrating my improvements. Fig. 2, is a view in longitudinal section, and Fig. 3, is a view in cross section.

1, 1, represent longitudinal bars which are 35 secured by rivets 2, to end brackets 3, and 4, respectively. Each of these end brackets is composed of a single sheet metal blank, which is bent forming a base member 5, and 40 upright angles 6, with an end plate 7, said end plate secured by rivets 2, to the angular uprights 6.

The side portions of the uprights 6, extend 45 above the end portions so that the end portions provide shoulders 8, on which one end of a hinged cover 9, is supported in horizontal position. The side members of the angular uprights at the other end of the device, have extensions 10, which support a cross rod 11, on which the top 9, is hinged, 50 said top 9, having a depending flange 12, at one edge, made with an opening to receive rod 11, and a perforated ear 13, is provided at the other edge of top 9, to receive the rod 11. This top 9, as above stated, 55 is provided at one side with a depending flange 12, and is also provided at its oppo-

site side with an upwardly, projecting flange 14, constituting a scraper against which the shoes are to be scraped to free them from mud clinging thereto.

One end of the top 9, is provided with an upwardly curved extension 15, which is adapted when depressed to elevate the cover 9, and throw it back to the position shown in Fig. 2, so as to expose the upwardly projecting bristles 16, of a brush 17.

The brush 17, is supported in the framework of the device, and is normally protected by the cover 9, but access may be had to the brush by depressing the extension 15, to throw the cover up.

The bars 1, 1, are preferably provided with openings 18, for the reception of securing devices, to permanently attach my improvements, so as to prevent movement of 75 the device or its unauthorized removal.

My improvements are preferably composed entirely of sheet metal, the framework or casing comprising the two bars 1, the end portions 3, and 4, riveted thereto, 80 and the top 9, with the brush 17, inclosed.

It will be noted that the side members of the angular uprights at both ends of the frame project above the cover, when the latter is in closed position. This greatly 85 strengthens the structure, and holds the cover properly positioned relative to the frame, regardless of the lateral stresses to which it is subjected when the shoes are being scraped. I do not, however, limit myself to this precise construction, nor to the 90 various details set forth, but consider myself at liberty to make such changes and alterations as fairly fall within the spirit and scope of the appended claims.

Having thus described my invention what I claim as new and desire to secure by Letters Patent is:

1. In a shoe cleaning device, the combination of a frame comprising longitudinal base 100 bars, end bars secured to said base bars and having angular uprights, a rod connecting the uprights at one end of the frame, a brush supported within the frame and having its bristles projecting upwardly, a cover comprising a single piece of sheet metal bent downward at one edge adapted to partially inclose the brush, bent upward at its other edge forming a scraper, a perforated ear on said last-mentioned edge of the cover, 105 said first-mentioned downwardly bent portion having an opening registering with the 110

- opening in said ear to receive said rod, and an upwardly bent end on said cover adjacent its pivotal support on the rod, substantially as described.
- 5 2. In a shoe cleaning device, the combination of a frame comprising longitudinal base bars, end bars secured to said base bars and having angular uprights, a rod connecting the uprights at one end of the frame, a brush supported within the frame and having its bristles projecting upwardly, a cover comprising a single piece of sheet metal bent downward at one edge adapted to partially inclose the brush, bent upward at its other edge forming a scraper, a perforated ear on said last-mentioned edge of the cover, said first-mentioned downwardly bent portion

having an opening registering with the opening in said ear to receive said rod, an upwardly bent end on said cover adjacent its 20 pivotal support on the rod, and the side members of said angular uprights projecting above the cover when the latter is in its closed position, whereby lateral bending movement of the cover is prevented when scraping action is had thereon, substantially as described.

In testimony whereof I have signed my name to this specification in the presence of two subscribing witnesses.

MARCENE BENN.
